(57) **CLAIM**

The ornamental design for a conical cutting element, as shown and described.

DESCRIPTION

FIG. 1 is a perspective view of the conical cutting element showing our new design; and,

FIG. 2 is a side view of the conical cutting element of FIG. 1. The broken line showing of a lower portion of a cutting element is included for the purpose of illustrating environmental structure and forms no part of the claimed design.

1 Claim, 2 Drawing Sheets

FIG. 1

FIG. 2
